LIFTING AND LOWERING APPARATUS.

1,253,179.

Specification of Letters Patent. Patented Jan. 8, 1918.

Application filed January 8, 1917. Serial No. 141,203.

To all whom it may concern:

Be it known that I, WILLIAM F. IRRGANG, a citizen of the United States of America, residing at Windsor Locks, in the county of 5 Hartford and State of Connecticut, have invented certain new and useful Improvements in Lifting and Lowering Apparatus, of which the following is a specification.

This invention relates to improvements in 10 lifting and lowering apparatus and, while the invention may be applied generally, it finds one preferred specific use as a means for lifting and lowering casters. Casters of the elevating type are disclosed in my prior 15 Patent No. 1,174,582, granted March 7, 1916.

Casters of the elevating type as disclosed in this patent comprise a wheeled frame adapted for attachment to the leg of a bed, table, or the like, to support the latter in the 20 usual manner, together with mechanism whereby the caster frame may be raised when desired to lift the wheel from supporting engagement with the floor, the weight of the article on the caster frame 25 being supported independently of the wheel. Such casters are particularly useful in hospitals, for example, as supporting devices for beds, operating tables and the like, for while it is frequently necessary to roll the 30 bed or table from point to point, it is at all other times desirable to prevent the supported body from rolling, so that it cannot be readily displaced. A further advantage 35 of casters of the type described lies in increased life of the caster wheels, particularly when rubber tired wheels are employed, for, when the wheels are not in use, all weight may be removed therefrom.

The broad object of this invention is to 40 provide in a lifting and lowering apparatus, a jack mechanism with an actuating member therefor and an automatic means to alternately set the jack mechanism for lifting and lowering operations, so that successive 45 actuations of the member will alternately raise and lower the mechanism.

An object of this invention is to provide 50 a caster of the class described wherein a single lever is exposed for actuation, which, when successively depressed, will alternately effect a raising and lowering of the caster, together with a positive locking of the parts in raised position and a positive release of

the parts as the frame is lowered, without relying on the skill of the operator for successful operation. 55

Another object of the invention is to provide a caster frame having a wheel mounted in offset relation to the vertical axis of the frame, a plunger slideable in the frame in 60 line with the axis of the latter, a lever to depress said plunger to the floor and thereafter raise the frame with the plunger as a fulcrum, means to lock the plunger in raised position, and devices operable on a subsequent depression of the lever to release said means and permit the frame to be lowered 65 under the control of the operator.

Other objects and advantages will appear in the description to follow and will be particularly pointed out in the appended claims. 70

Referring to the drawings as illustrating one preferred manner in which the invention may be practised—

Figures 1 and 2 are side and front elevational views, respectively, of the caster with the wheel thereof in lowered position; 75

Fig. 3 is a plan view of Fig. 1;

Fig. 4 is a sectional elevation taken on the line 4—4 of Fig. 3; 80

Fig. 5 is a view, taken similarly to Fig. 4, showing the wheel in raised position and the parts in the relative positions which obtain at the end of the lifting movement;

Fig. 6 is a view similar to Fig. 5 showing 85 the relative positions of the parts which obtain after the operating lever is released at the end of the lifting movement;

Fig. 7 is a sectional plan view taken on the line 7—7 of Fig. 6; 90

Fig. 8 is a cross sectional view taken on the line 8—8 of Fig. 6; and

Fig. 9 is a detail view showing the connection of the springs to the trip finger. 95

The invention although capable of general application, will be described for illustrative purposes in one of its specific uses, namely, as a lifting and lowering means for a caster.

Referring to the drawings in detail; the 100 caster frame comprises a vertically disposed hollow semi-cylindrical portion 10 from which a pair of integral wings 11 extend laterally in spaced parallel relation, as best shown in Figs. 3 and 7. An axle 12, fixed in wings 11, rotatably supports a suitable 105 easter wheel 13, which is rotatable between

the wings, as clearly shown in Fig. 3. Fixed in a bridge 14 connecting the upper parts of the wings 11 and arranged in axial alignment with the portion 10 is a vertically arranged pin 15 which is adapted to fit into a socket in the leg *a* of the bed, table, or the like to be supported. At its base, the hollow cylindrical portion 10 is provided with a short integrally formed ring 16 (Figs. 4, 7 and 8) which, together with portion 10, forms a cylindrical bore to receive a plunger 17. The latter is also of general hollow cylindrical form but has a cut away portion 18, as best shown in Figs. 4 and 8, to clear the rear of wheel 13. At its base the plunger 17 is provided with a suitable foot 19, preferably of rubber or the like, to engage the floor, when wheel 13 is raised in a manner to be described. A slot 20 (Figs. 2 and 7) is formed in the front face of portion 10 and a ledge 21 integrally formed on plunger 17 extends laterally from the plunger through and beyond this slot. Pivoted at 22 to member 10 is a foot lever 23 and depending therefrom is a projection 24 which, when the lever is depressed, is adapted to engage the upper surface of ledge 21 and thus depress plunger 17.

Within plunger 17 and pivotally connected thereto by a pin 25 is a latch which comprises two spaced upwardly extending arms 26 (Figs. 7 and 8) connected together near the pivot 25 and provided with a horizontal and forwardly extending finger 27 (Figs. 4 and 7). Arms 26 have recesses 28 (Fig. 4) in their upper ends which, when wheel 13 is raised, are adapted to be forced in under a pin 29 fixed to and extending between wings 11, whereby plunger 17 may support the caster frame. The upper end of plunger 17 is cut to form two spaced parallel vertical surfaces 30 which, as shown in Figs. 7 and 8, engage pin 29 and are slideable thereon. These surfaces form a guide for the upper part of the plunger to supplement the relatively small guiding surface presented by ring 16 and also effectually hold the plunger from turning. At the intersection of surfaces 30 with the cut out portion 18, 50 a horizontally arranged shoulder 31 is formed which, when wheel 13 is lowered as in Fig. 4, abuts pin 29 and limits the upward travel of the plunger.

The finger 27 is provided at its outer end with a depending projection 32, and engaging the under side of finger 27 is a trip finger 33, which has a hook-shaped lower portion to engage the projection, the latter serving to prevent the trip finger from forward displacement. Wings 34 (Fig. 7) project from finger 27 on either side of finger 33 and prevent side displacement of the latter. Trip finger 33 extends upwardly and is bent forwardly into a recess formed in ledge 21 (Figs. 4 and 7) and extends slightly

above the latter as shown in Fig. 4, the lever 23 also being recessed as shown in Fig. 4 to receive the trip finger. The latter has a rearwardly extending wing 35 which is movable between the latch arms 26, and a spring 36 connects this wing to a hook 37 on the rear of lever 23. A compression spring 38 is fixed at one end in the under side of wing 35 and its other end normally rests loosely against the upper side of finger 27 without exerting any force thereon. Preferably springs 36 and 38 are made from the same piece of wire, a part of which is closely wound to form spring 36 and the other part is open wound to form compression spring 38, as shown in Fig. 9. These two portions are connected by a short straight portion 35' which is secured to the wing 35. One advantageous way of fixing the portion 35' in wing 35 is to slit the latter from its rear end with a saw, insert portion 35' in the slit, and thereafter close up the slit by hammering on the sides of the wing, leaving the portion 35' embedded in wing 35 as shown in Fig. 9.

Normally spring 36 is subjected to very little tension, whether wheel 13 is lowered, as in Fig. 4, or raised as in Fig. 6, although in the latter instance the tension is somewhat greater than in the former. With the wheel lowered, as shown in Fig. 4, spring 36 has just sufficient tension to hold shoulder 31 of plunger 17 against pin 29 and to hold the trip finger 33 and latch 26 in the positions shown. When, however, lever 23 is depressed spring 36 is elongated rapidly since one extremity is being lifted by the depression of lever 33 and the other extremity is being lowered by downward movement of plunger 17.

As lever 23 is depressed, projection 24 engages ledge 21 and forces the latter downwardly. Latch 26, since it is connected to the plunger, also is forced downwardly and carries with it the trip finger 33. The latter is prevented from swinging to the right, as viewed in Figs. 4, 5 and 6, by the surface 39 of lever 23 (see Fig. 5) and spring 36 constantly pulls upwardly on the trip finger and by the engagement of the latter with finger 27 forces latch arms 26 to the left so that they bear against pin 29. On continued downward movement of plunger 17, the foot 19 will engage the floor and further depression of the lever will raise the caster frame (the ledge 21 serving as a fulcrum) so that wheel 13 will be lifted out of contact with the floor. After wheel 13 has been lifted a slight amount from the floor, recess 28 in the latch arms 26 will come below pin 29 and the latch arms will be forced to the left into the position shown in Fig. 5. Now, if the pressure on lever 23 be relaxed to slightly lower the caster frame, pin 29 will drop into recesses 28 so that the weight of the member

supported by leg α will come upon the latch arms 26 and be transmitted through pivot 25 and plunger 17 to the floor. It is to be noted particularly that the weight supported on leg α is transmitted substantially in a straight line to the floor, since pivot 25 and pin 29 lie close to the vertical axis of pin 15.

As the pressure is removed from foot lever 23, spring 36 immediately throws the lever upwardly into abutment with the under side of bridge 14 and trip finger 33, which has been held by surface 39 of the lever is thrown to the right into the recess in ledge 21, all as shown in Fig. 6. The contraction of spring 36 does not, however, tend to withdraw to latch arms 26. It is to be noted that the foot lever, when not in use, always occupies substantially the same position relatively to the caster frame as will be seen from a comparison of Figs. 4 and 6. The parts, now positioned as shown in Fig. 6, are arranged so that a subsequent depression of lever 23 will release the latch arms 26 and allow the caster to be lowered to the floor under the control of the operator. Thus as lever 23 is depressed, the part 24 first engages the upper face of trip finger 33 and depresses it to the level of ledge 21. Further movement of lever 23 will lift the 30 caster frame relatively to the plunger 17 and thus raise pin 29 out of recesses 28 in the latch arms 26. Spring 36 is elongated and put under tension, but trip finger 33 cannot be pulled upwardly by the spring since it is engaged by projection 24. The spring 38 becomes compressed against the finger 27 as finger 33 is depressed by the lever 23 and as pin 29 is raised from the latch arms, the compressed spring 38 forces finger 27 downwardly and thus causes arms 26 to move to the right out of the path of pin 29. As trip finger 33 is depressed, the rounded end of projection 24 eventually rests in the rounded recess in the upper end of finger 33 so that the latter is held from moving to the right or from moving upwardly. The arrangement is such that spring 38 is caused to act against finger 27 to hold arm 26 out of the path of pin 29 until the wheel 13 has been lowered and until plunger 17 has moved upwardly a sufficient distance to bring the recesses 28 above the pin. The operator, after arms 26 have been withdrawn, still has his foot on lever 23 so that wheel 13 may be lowered gently to the floor. Thereafter, as lever 23 is released, spring 36 draws the latter and plunger 17 upwardly and trip finger 33 is thrown to the right, the parts being automatically returned into the positions shown in Fig. 4.

It will be obvious that the caster device described may readily be converted into a jack by simply omitting the caster wheel 13 and cutting off the parts of the wings 11 which protrude beyond the members 14 and

16. The foot 19 will then be the floor engaging portion at all times instead of only engaging the floor when the jack mechanism is raised, as heretofore. Thus by the simple omission of parts described an operable jack mechanism is obtained which may be used for any desired purpose.

The construction described is characterized by the provision of a single operating lever which, when successively depressed, will successively cause the raising and lowering of the caster wheel. By this arrangement, the operator cannot do the wrong thing as is possible when, as heretofore, two levers are exposed for actuation. The exercise of judgment on the part of the operator is unnecessary for successful manipulation of this device since only one lever is available for actuation and since this lever can be actuated in but one way, namely, by depression and release. There have been casters, wherein a single operating lever has been exposed for operation, but the described structure is to be distinguished from such casters by its arrangement for fool-proof operation. Thus, with single lever casters, as heretofore used, automatic means operable by depression of the lever have been provided to lock the caster in raised position, which means are arranged to be released upon a further depression of the lever. Such devices are perfectly satisfactory when used with care and skill, but they do require the exercise of personal judgment for successful operation. Thus, the operator as he depresses the foot pedal must "feel" when the locking means operates and must take care not to further depress the pedal or these same means will be released and the caster with the weight thereon will drop unexpectedly to the floor as the pedal is released. The present structure cannot be so manipulated. Thus, lever 23 may be depressed as far as possible to bring recesses 28 below pin 29, but arms 26 will be continually forced toward the pin until the lever 23 has been released for, as shown in Fig. 5, the trip finger 33 is held by surface 39 of the lever from moving to the right so that the trip finger is positively kept out of the path of projection 24 and as long as this condition obtains the latch arms cannot be released. Thus, a positive locking of the caster frame in raised position is provided. Similarly, when on a subsequent depression of the foot lever, arms 26 are retracted, these arms are positively held retracted until the caster frame is lowered. There is no possibility for the arms 26 to snap into locking position until the pin 29 has been first lowered below recess 28 and then raised again. Thus, the mechanism operates automatically by foot lever 23 and correct operation is obtained without reliance on the skill of the operator, in fact

the human intelligence has been eliminated as a factor in the successful operation of the caster.

The invention has been described in a 5 preferred form for illustrative purposes, but the scope of the invention is defined by the appended claims rather than by the foregoing description.

What I claim is—

- 10 1. A caster device comprising in combination, a frame, a plunger slidable therein, a lever pivoted to the frame and arranged to depress the plunger into engagement with the floor and thereafter lift the frame with 15 the plunger as a fulcrum, means to hold the frame in raised position, and means operable on a subsequent depression of the lever to release the first-named means and permit the frame to be lowered to the floor.
- 20 2. A caster device, comprising, in combination, a frame, a plunger slidable therein, a lever pivoted to the frame, and having a part extending outwardly therefrom for actuation and mechanism associated with the 25 plunger and constructed so that successive depressions of said lever will alternately effect a raising and lowering of said frame.
- 30 3. A caster device, comprising, in combination, a frame, a plunger slidable therein, a lever pivoted to the frame, resilient means connecting the plunger and lever and normally holding both retracted, said lever arranged when depressed to force the plunger to the floor and thereafter lift the frame 35 with the plunger as a fulcrum, and means on the plunger movable into engagement with the frame to hold the latter in raised position.
- 40 4. A caster device, comprising, in combination, a frame, a plunger slidable therein, a lever pivoted to the frame, resilient means connecting the plunger and lever and normally holding both retracted, said lever arranged when depressed to force the plunger to the floor and thereafter lift the frame 45 with the plunger as a fulcrum, means on the plunger movable into engagement with the frame to hold the latter in raised position, and devices operable on a subsequent depression of said lever to release said last-named means and permit the frame to be lowered and said resilient means to retract the plunger and lever.
- 50 5. A caster device, comprising, in combination, a frame, a plunger slidable therein, a lever pivoted to the frame, a latch pivoted

to the plunger, resilient means connecting the lever to said latch and adapted to hold the plunger and lever in retracted position, said lever arranged when depressed to force 60 the plunger into engagement with the floor and thereafter lift the frame with the plunger as a fulcrum, said latch adapted to be thrown by said means into engagement with a part of the frame when the latter is lifted 65 to lock the frame in raised position, and means to prevent the release of said latch until the lever has been drawn upwardly by said resilient means.

6. A caster device, comprising, in combination, a frame, a plunger slidable therein, a lever pivoted to the frame, a latch pivoted to the plunger, a pin in the frame adapted to be engaged by the latch, a trip finger having a part to engage said latch, resilient means connecting said finger and lever operable to throw the latch toward said pin, said lever arranged when depressed to force the plunger to the floor and to thereafter lift the frame with the plunger as a fulcrum, said 75 latch having a part arranged to be thrown into locking engagement with the pin to hold the frame in raised position, and yieldable means between the finger and latch, said finger having a part adapted to be engaged on a subsequent depression of the lever to compress said yieldable means, the latter arranged to retract the latch as the frame is raised on continued depression of the lever, whereby the frame may be lowered, said finger and yieldable means arranged to hold the latch retracted until the lever has been thrown upwardly by said 80 resilient means.

7. Lifting and lowering apparatus, comprising in combination, jack mechanism, a member to operate the latter and automatic means to alternately set said mechanism, for lifting and lowering operations respectively, on each of the successive operating cycles of 95 100 said member.

8. Lifting and lowering apparatus, comprising in combination, a support, a lifting member movable relatively thereto, means to move the support and member, the one relatively to the other, and mechanism automatically operable by relative movement of member and support in one direction to effect a relative movement between the member and support, in the other direction upon 105 a subsequent actuation of said means.

WILLIAM F. IRRGANG.
